UNITED STATES PATENT OFFICE.

ROBERT C. VOM CLEFF, OF HOBOKEN, NEW JERSEY.

MILLINERY-PLIERS.

1,077,672.

Specification of Letters Patent.

Patented Nov. 4, 1913.

Application filed June 3, 1911. Serial No. 631,029.

To all whom it may concern:

Be it known that I, ROBERT C. VOM CLEFF, a citizen of the United States of America, and a resident of Hoboken, in the county 5 of Hudson, State of New Jersey, have invented certain new and useful Improvements in Millinery-Pliers, of which the following is a specification.

This invention has reference to improvements in pliers such as are used for cutting wire for instance.

It is the special purpose of this invention to produce improved pliers which are particularly adapted for cutting fine wires and especially fine silk covered wires. Such fine silk covered wires are used in certain arts and trades particularly for millinery purposes in making and trimming hats and bonnets, for wiring plumes and ribbons and 15 in the manufacture of artificial flowers and the like. For cutting such fine silk covered wires some pliers heretofore used had cutting edges in their jaws which just met at the best when the pliers were closed. If, 20 however, such pliers were used for some time or if by inadvertence of an operator something heavier or harder was cut therewith the cutting edges did not meet perfectly. The consequence was that fine wires 25 could not be cut with such pliers any more and particularly the silk covering of the same could not be cut evenly and would leave a frayed edge or would even unravel for a certain length.

30 Other combination tools having knives or cutters which operate like shear-blades were constructed for specific purposes and not adapted for cleanly cutting fine silk covered wires as are used for millinery purposes.

It is the special purpose of this invention to produce improved pliers particularly for millinery purposes which cut the finest wires and their silk covering smoothly and evenly 45 and the pliers will retain this quality until worn out by general wear and tear.

The invention further consists in the combination, construction and arrangement of the detail parts as required for the specific purposes intended.

In order to make the invention entirely clear reference is had to the accompanying drawing in which:

50 Figure 1 represents in side elevation a pair of pliers for millinery and kindred purposes which embody in desirable form

the present improvements. Fig. 2 is a rear view of same. Fig. 3 is a detail view of the upper part of the pliers partly opened. Fig. 4 is a sectional view on line 4-4 of 60 Fig. 3. Fig. 5 is a sectional view on line 5-5 of Fig. 3, and Fig. 6 is a detail view on an enlarged scale in cross section in the same plane as Fig. 5 showing the covered wire in the moment of being severed. 65

Similar characters of reference denote like parts in all the figures.

Referring now to the drawing *a*, *b*, represent the jaws and *c*, *d*, are the handles which are preferably integral therewith as 70 usual. The noses *e*, *f*, are preferably narrow for purposes to be explained farther down. The meeting surfaces of the noses are cut in the usual manner. Each jaw is interiorly cut out forming partly a nearly 75 crescent-shaped incision *g* near the cutting edge while the rest of the incision is of usual construction as shown. The crescent-shaped incisions serve for taking up hair-like little threads projecting from the silk 80 thread which are separated when the wire is cut, and minute particles of metal and silk occurring when by inadvertence of the operator the wire has to be cut a second time. 85 The flaring portions of the recesses permit of the convenient passage of the wire as usual. On the jaw *a*, however, there is an attachment *h* which consists of a steel plate secured to said jaw by means of the pivot *i* that connects both halves of the pliers. Thus 90 the jaw *a* serves as a support for the cutting attachment *h*. The attachment *h* nearly extends to the side end of the jaw *a*. At its outer end it extends to about the inner end of the nose *e* while the upper inner end portion of said attachment forms a cutting edge *h*¹ that extends toward the handle in a slanting direction beyond the straight line 95 of the file cut nose *e* so that the cutting edge begins at the inner end of the straight surface of the file-cut nose *e* and reaches over the jaw *b* to a certain extent when the pliers are in a closed condition as illustrated in Fig. 1.

100 In order to prevent any lateral movement of the attachment the same is provided with a slight extension *h*² through which a screw *j* or bolt passes. As shown in Figs. 1 and 3 the screw or bolt *j* passes into the inner portion of the handle *d* formed integrally 105 with the jaw *a* so that the attachment is secured at two points. The extension *h*² is 110

about as wide as the adjoining top surface of the handle *d*. For the purpose of preventing sharp outer edges on the attachment the same is beveled off all around except the extension *h*². In Fig. 3 of the drawing the pliers are shown as partly opened. It is plainly seen from this figure that the slanting cutting edge *h*¹ of the attachment *h* overlaps the straight cutting edge *b*¹ formed on the jaw *b*. Upon closing the pliers the two cutting edges perform a shear-like motion and possess a shear-like action by virtue of the attachment and its slanting cutting edge that overlaps the straight cutting edge of the jaw *b*. Any wire, bare or silk-covered, no matter how fine, will be cleanly cut by these pliers leaving a smooth cutting edge and without distorting the silk covering. Under no circumstances will these pliers get into a condition not to cut fine wires.

The shearing action of the present pliers is performed from the beginning of closing the same to the end. Thus an exceedingly reliable cutting tool for fine wires has been produced and in addition thereto the narrow fine file-cut inner surfaces of the noses permit of making twists, bends and knots in the wire by a simple motion of the hand.

30 I claim as my invention:

1. Millinery pliers for cutting fine silk covered wires comprising a pivoted pair of handled jaws each cut out so as to form a crescent - shape incision and a transverse

flaring main recess, a straight cutting edge 35 formed on the middle portion of one of its sides, and a cutting attachment secured to the second jaw by means of the pivot and with its inner end to the handle of said second jaw, said attachment having a cutting 40 edge extending inwardly toward the handle in a slanting direction overlapping the cutting edge portion of the first jaw when the pliers are closed.

2. Millinery pliers for cutting fine silk 45 covered wires comprising a pivoted pair of handled jaws, noses thereon with opposed roughened grasping faces and at one side opposed straight edges with inclined bottoms forming conjointly a flaring recess 50 across the jaws, said bottoms having each a second recess of crescent-shape beginning at said straight edge and deepening therefrom across the jaw to its curved boundary, and a cutting attachment secured to the sec- 55 ond jaw by means of the pivot and with its inner end to the handle of said second jaw, said attachment having a cutting edge ex- 60 tends inwardly toward the handle in a slanting direction overlapping the cutting edge portion of the first jaw when the pliers are closed.

Signed at New York, N. Y., this 2nd day of June, 1911.

ROBERT C. VON CLEFF.
